UNITED STATES PATENT OFFICE.

HENRY F. MERRIAM, OF WEST ORANGE, NEW JERSEY, ASSIGNOR TO GENERAL CHEMICAL COMPANY, OF NEW YORK, N. Y., A CORPORATION OF NEW YORK.

SULPHUR BURNER.

Application filed December 3, 1923. Serial No. 678,098.

This invention relates to burners adapted for the burning of sulphur particularly sulphur of the kind commercially known as brimstone. The object of the invention is 5 to improve this type of furnaces and to render their operation more efficient, as will be made to appear in the subjoined description.

Heretofore rotary furnaces for the burning of brimstone were operated under a 10 slight minus pressure, the air for the combustion being drawn into the furnace by appropriate means located at some point further along in the process. Burners of that type are not adapted to work under 15 pressure. One of the features of the new furnace is that it is adapted to be operated under pressure, a blower forcing air into the burner against pressure caused by resistance of subsequent apparatus. In other 20 words, the operation is conducted under positive pressure. This conception assures a supply of clean air, dried or moist, which is under control and can be forced into the furnace in regulated quantities to cause 25 burning and volatilization of the sulphur. Sufficient air may thus be forced into the combustion chamber to complete the oxidation of the volatilized sulphur and to bring about any desired dilution of the SO_2 gas, 30 so as to prepare it for use for a variety of manufacturing purposes, such as paper pulp making, sulphuric acid manufacture or other purpose for which SO_2 gas is required. An 35 apparatus operating under positive pressure will require to be made gas-tight, and suitable provision to that end is made in the apparatus of this application.

It will be observed that among the results of the invention is the provision of apparatus of improved efficiency and economy 40 and by means of which larger quantities of sulphur than heretofore can be volatilized, completely burned and diluted as desired, all in shorter time than in the apparatus heretofore used. Incidentally the improvements 45 also include means by which the difficulties caused by burning under pressure, such as leakage and over-heating of the bearings, are eliminated.

The accompanying drawing illustrates the invention as embodied in a preferred form thereof, and in this drawing Fig. 1 is a vertical longitudinal section, Fig. 2 a vertical cross-section through line A—A of Fig.

1 and Fig. 3 an end view of the burner of 55 Fig. 1.

The burner shown in the drawing consists of a suitable supported cylindrical, horizontally disposed, container A in which a cylindrical drum B is mounted on a rotatable central shaft 12, whose ends protrude through the end walls 13 and 14 of the housing. The drum B consists, in the embodiment shown, of two nested concentric cylinders 11 and 11^a which are open at the 60 ends. These cylinders preferably have holes 15 which provide communication between the concentric spaces of the drum and the casing for better circulation of the gases. The number of location of these apertures 70 15 as well as the number of cylinders 11 may obviously be varied according to requirements.

On one side of the cylindrical casing, preferably near the center of the cylindrical casing, there is a storage and feed-hopper 16 through which the sulphur or brimstone is fed in such a manner that it enters the casing A near its bottom already in liquid or semi-liquid condition (see Fig. 2). A depending portion 10^a of the cylindrical casing provides a partition separating the tangential inlet 10^b from the interior of the burner. The lower portion of the hopper 16 is formed by an eccentric extension 16^a 75 of the bottom of the casing and by the depending partition 10^a, the latter extending downwardly to a point below the normal level of the liquid sulphur in the casing, thereby providing a liquid seal. This liquid 80 seal feeding device forms a permanent barrier against the escape of gas from the burner to and through the feeding hopper 16. As the sulphur becomes liquid in the lower 85 part of the feed-hopper, which is exposed to the heat existing in the burner, a column of liquid sulphur will stand in the lower part of the feeder above the level of the liquid sulphur standing in the casing of the burner 90 as indicated in Fig. 2, so that the liquid 100 column in the feeder will balance the excess pressure existing in the burner. Therefore no sulphur can be thrown out of the hopper and no gas can escape. The melting of the sulphur in the hopper also has the effect of 105 eliminating moisture and drying the sulphur before it enters the burner. For controlling the level of the sulphur standing in

the burner inspection cocks 17 are arranged at the rear end wall of the casing. As the drawing shows, the surface of the sulphur-bath is kept at such a height that both of 5 the cylindrical sections 11 and 11^a of the drum B dip into the liquid sulphur while rotating, so that they carry with them a film of liquid sulphur to be exposed to the air under pressure. At 16^b (Fig. 2) there 10 is indicated a cleaning door just above the level of the molten sulphur in the feeding hopper 16.

For blowing the air into the burner, a blower 5 supplies pressure air (which may 15 be preliminarily dried) through a pipe connection 18 communicating with the upper part of the front end wall or head 13 of the casing, and between this air inlet and the front end of the rotary cylinder there is a 20 partition wall 19 depending, extending downwardly beyond the shaft 12 of the drum. In this partition wall openings 20 are so arranged that the air is blown into the concentric sections of the rotary drum. 25 One part of the air circulates around the shaft near the stuffing box 22 to cool the latter and finds its outlet at 4 between the depending end of the partition wall and the head of the casing near the level of the 30 sulphur-bath, so that this current of air strikes the surface of the sulphur-bath immediately.

The holes 15 in the cylinders of the drum provide better circulation of the gases 35 through the entire apparatus.

After having circulated through the whole length of the burner, the gas produced in the burner is carried off through an air-tight pipe 28 into the combustion chamber C where the gas and vapor are mixed 40 with an additional quantity of air under pressure from the line 29.

To prevent loss of heat by radiation the casing of the burner A is provided with an 45 insulating covering 24.

To prevent gas under pressure from leaking through the end bearing of the shaft, the end of the latter and the bearing at the 50 exit end of the burner are covered tightly by a cap 25.

A drain 26 is arranged in the rear wall 55 near the bottom of the casing to permit the draining of residual sulphur when, after extended operation, an accumulation of the impurities render such draining necessary. A manhole 27 is also provided in the wall 14 to provide for access to the interior of the apparatus whenever this may be required.

60 The aforementioned combustion chamber C is connected with the burner A by the pipe 28 which is arc-shaped and opens into a dome C' of the combustion chamber C which is preferably set up on legs so that its bottom is air-cooled and protected from

over-heating. A branch 29 of the air pipe protrudes through the side wall of this dome and forms in the center of the latter an elbow, the vertical discharging end of which opens into the combustion chamber just below the dome, so that the air blast acts like an injector upon the gases and vapors coming from the burner; a short distance below the exhaust end of the elbow pipe 29 an arch 30 is built into the combustion 70 chamber. Said arch 30 forms a baffle plate 30^a against which the forced gas current strikes, so that it is reverberated. It will be understood that thereby a very complete mixture of the gases and vapors with the 80 air and complete combustion is obtained.

The arch-shaped partition 30 has, surrounding its baffle plate portion 30^a, a plurality of openings 31 through which the burning gases are distributed and directed into a 85 second compartment 32 of the combustion chamber in which the distributed currents converge towards a central opening 33 in a second partition arch through which the combustion gases enter into a lower compartment 34 from which the gas or mixture of 90 gas and air is tapped for its use through 35.

Instead of utilizing the pressure air from 18 to cool the stuffing box 22 at the front end of the furnace, cooling at this point may be 95 effected by means of water. Water cooling may also be employed in connection with the bearing covered by the cap 25. The exit pipe 28 from the burner A rising vertically prevents physical impurities from being carried over into the combustion chamber C. At the lower end of this pipe there is a vent 6 for starting combustion in the burner A. The chamber under the burner A may also be developed as a fire box to 105 heat up the burner from the outside when necessary. The use of the rotating cylinders 11 and 11^a to pick up a film of molten sulphur and to expose it to the air for burning also permits making the burner shorter 110 and of less weight, thereby simplifying construction and reducing cost and giving a larger capacity to the burner due to the intimate contact of air and sulphur and the large exposure of sulphur.

115 It will be understood that the combustion chamber C may be built with only two, or with more than three, compartments, and that changes may be made in the construction of the rotary burner without departing from the spirit and scope of the invention.

120 Although the apparatus is especially effective when used in a system employing positive pressure, it will be apparent that the novel features of construction involved in the sulphur burner and the hopper feed and other details may also be used in a system which is operated under suction and those claims of this patent which are 125 directed to the details of construction are 130

intended to cover such details whether used in a system operating under suction or under positive pressure. Primarily, however, the preferred operation is the one conducted 5 under positive pressure. In that case, for example, the blower 5 is protected against deterioration from gases since it handles clean air. In a suction system the gases which pass through the suction producing 10 instrumentalities are hotter and generally contain traces of sulphuric acid.

Having described the operation of the apparatus in connection with the detailed 15 description thereof, I consider that it will not be necessary to make an extended statement of the operation.

I claim:

1. A sulphur burner (brimstone burner) 20 comprising a casing forming a burner chamber and having an inlet for feeding sulphur to said chamber and another inlet for admitting compressed air to said chamber, and means for forming a permanent barrier to the passage of gases or such air from the burner chamber through the sulphur feed inlet.

2. A sulphur burner (brimstone burner) 25 comprising a casing forming a burner chamber and having an inlet for feeding sulphur to said chamber and another inlet for admitting compressed air to said chamber, and means for forming within said chamber a liquid seal barring the passage of gases or such air from the burner chamber through the sulphur feed inlet.

3. A sulphur burner (brimstone burner) 30 comprising a casing forming a burner chamber and having an inlet for feeding sulphur to said chamber, another inlet for admitting air under pressure to said chamber, and a partition depending into said chamber adjacent to the sulphur inlet to a point below the normal level of the molten sulphur in said chamber, whereby such molten sulphur will 40 form a liquid seal to prevent the passage of gases or air out of said chamber through the sulphur inlet.

4. A sulphur burner (brimstone burner) 45 comprising a casing forming a burner chamber and having an inlet for feeding sulphur to said chamber, and means for forming a permanent barrier to the passage of gases or air from the burner chamber through the sulphur feed inlet.

5. A sulphur burner (brimstone burner) 50 comprising a casing forming a burner chamber and having an inlet for feeding sulphur to said chamber, and means for forming within said chamber a liquid seal barring the passage of gases or air from such chamber through the sulphur feed inlet.

6. In a sulphur burner (brimstone burner) 55 of the character described the combination with a burner-casing, of a cylindrical drum rotatably mounted in said casing open at

both ends and consisting of a plurality of open cylinders concentrically arranged and adapted to carry a plurality of films of liquid sulphur from the sulphur-bath, means for causing currents of air to pass over the 70 sulphur films, means for feeding sulphur into the burner without leakage and means for preventing leakage of sulphur vapors through the bearings of the drum-shaft.

7. A sulphur burner (brimstone burner) 75 comprising in combination, a horizontally disposed cylindrical burner-casing, a hopper for feeding sulphur into the casing, the bottom of said hopper being formed by a part of the cylindrical casing, while an extended part of the bottom of the casing forms a side wall of the hopper, an opening being formed between said cylindrically-curved bottom and said side wall of the hopper adapted to feed the sulphur under the surface of the sulphur-bath and means for forcing air through the burner-casing.

8. A sulphur burner (brimstone burner) 80 comprising in combination, a horizontally disposed cylindrical burner-casing, a hopper for feeding sulphur into the casing, the bottom of said hopper being formed by a part of the cylindrical casing, while an extended part of the bottom of the casing forms a side wall of the hopper, an opening being formed between said cylindrically-curved bottom and said side wall of the hopper adapted to feed the sulphur under the surface of the sulphur-bath, means for causing air to pass through the burner-casing, a cylindrical 90 drum comprising a plurality of cylinders mounted on a rotatable shaft in the burner-casing, the means for causing air to pass into the burner being adapted to direct the air against the surfaces of the drum.

9. A sulphur burner (brimstone burner) 95 comprising in combination, a horizontally disposed cylindrical burner-casing, a hopper for feeding sulphur into the casing, the bottom of said hopper being formed by a part of the cylindrical casing, while an extended part of the bottom of the casing forms a side wall of the hopper, an opening being formed between said cylindrically-curved bottom and said side wall of the hopper adapted to feed the sulphur under the surface of the sulphur-bath, means for forcing air through the burner-casing, a cylindrical drum comprising a plurality of cylinders mounted on a rotatable shaft in the burner-casing, means adapted to force currents of air against the surfaces of the drum and means to cool the stuffing box of the shaft.

10. A sulphur burner (brimstone burner) 100 comprising a casing forming a burner chamber and having an inlet for feeding sulphur to said chamber, and a partition depending into said chamber adjacent to the sulphur inlet to a point below the normal level of the 110 molten sulphur in said chamber, whereby 115

4
such molten sulphur will form a liquid seal to prevent the passage of gases or air out of said chamber through the sulphur inlet.

11. A sulphur burner (brimstone burner) comprising a casing of substantially circular cross section provided with a substantially tangential inlet for the feeding of sulphur and a partition of circular curvature in the continuation of said inlet, said partition having its lower edge at a level below the normal level of the molten sulphur in said casing, and a rotary drum within said casing and adjacent to said partition, said drum having its lower portion below the normal level of the molten sulphur in said casing.

12. A sulphur burner (brimstone burner) comprising a casing forming a burner chamber, a rotary drum located within said casing and having its lower portion below the normal level of the molten sulphur in said chamber, and a stationary partition located adjacent to one end of said drum and provided with inlets to admit air to the interior of the drum.

13. A sulphur burner (brimstone burner) comprising a casing forming a burner chamber, a rotary drum located within said casing and having its lower portion below the normal level of the molten sulphur in said chamber, and a stationary partition located adjacent to one end of said drum and provided with inlets to admit air to the interior of the drum, said partition terminating adjacent to the end wall of the casing, at a point slightly above the level of the molten sulphur, to direct air over the surface of such sulphur.

14. A sulphur burner (brimstone burner) comprising a casing forming a burner cham-

ber, and a peripherally perforated rotary drum located within said casing and arranged to dip into the bath of molten sulphur contained in said chamber during normal operation.

15. A sulphur burner (brimstone burner) comprising a casing forming a burner chamber for molten sulphur, a combustion chamber having an inlet for the gaseous mixture formed in the burner chamber, a conduit connecting the outlet of the burner chamber with the inlet of the combustion chamber, an air-admission pipe terminating within said inlet and facing in the same direction, to act after the fashion of an injector, and a baffle arranged within said combustion chamber and having a solid portion opposite said inlet.

16. In combination with a sulphur burner (brimstone burner) adapted to burn sulphur under positive pressure, comprising a casing forming the burning chamber for molten sulphur provided with an outlet and a rotary drum in said casing, a combustion chamber which is provided with an inlet, a conduit connecting the inlet of the combustion chamber with the outlet of the burner and directed downwardly into said combustion chamber, means for blowing air into the combustion chamber and for completing combustion under positive pressure, comprising an air admission pipe terminating within said inlet and directed downwardly, said combustion chamber being equipped with means for reverberating and mixing the gas and air currents.

In testimony whereof I have hereunto set my hand.

HENRY F. MERRIAM.
